UNITED STATES PATENT OFFICE

WILLIAM D. HOXIE, DECEASED, LATE OF WESTERLY, RHODE ISLAND, BY LAVINIA B. HOXIE, OF WESTERLY, RHODE ISLAND, ISABELLE HOXIE MIDDLETON, OF GREENWICH, CONNECTICUT, AND THE WASHINGTON TRUST COMPANY, OF WESTERLY, RHODE ISLAND, EXECUTORS, ASSIGNOR TO THE BABCOCK & WILCOX COMPANY, OF BAYONNE, NEW JERSEY, A CORPORATION OF NEW JERSEY

WATER TUBE BOILER

Original application filed December 20, 1920, Serial No. 431,975. Divided and this application filed July 23, 1927. Serial No. 207,905.

This invention relates to water tube boilers, particularly of the type adapted for marine use, this application being a division of application Serial No. 431,975, filed December 20, 1920.

One of the objects of this invention is to produce a boiler which will be compact in form and efficient in operation. Another object of this invention is to provide a boiler which will have a minimum tendency to form scale if the feed water for the boiler is impure.

With these and other objects in view, this invention consists in the constructions hereinafter described and specifically pointed out in the appended claims.

In the accompanying drawings, Figure 1 is a front elevation, partly in section, of an illustrative form of boiler to which this present invention has been applied, and Fig. 2 is a side elevation of the illustrative boiler with parts of the outer wall broken away.

Similar reference numerals indicate similar parts in the several views.

In modern marine boiler practice, it is frequently desirable to provide superheated steam. It is also desirable that such superheated steam may be provided efficiently without seriously departing from the type of boilers which have come into common use for marine work. It is also desirable to design such boilers so that, so far as possible, the heat of the furnace will not be wasted by passing into the boiler room to the discomfort of the operators. The boiler of the present invention is designed to accomplish these purposes.

In the illustrative form of boiler, 10 is an upper water drum and 11 and 12 lower water drums, the latter being spaced apart to accommodate a furnace chamber between them, this furnace chamber being of any desired form and, in the instance illustrated, being adapted for oil fuel, the oil being introduced through burners projected through the openings in the furnace shown in the drawings. Each of the drums 11 and 12 are connected with the upper drum by a set of water tubes 12', 13. For reasons which will be explained more fully hereinafter, in the

form of boiler illustrated, the upper drum 10 is provided with water compartments 14, 15, which, as shown best in Figure 2, are preferably located centrally crosswise of the boiler and are much shorter than the length 55 of the drum 10. The drums 11 and 12 are also provided with compartments 16, 17 which extend the entire length of the lower water drums. The two rearmost rows of tubes 18, 19 are divided into three groups 60 of tubes, the tubes of the central group connecting the compartment 15 with the compartment 17 on one side of the boiler, and a similar group of the set 12 connecting the compartment 14 with the compartment 16. 65 The remainder of the tubes of the rows 18, 19 which come in front and at the rear of the compartment 15, connect the compartments 16 and 17, respectively, with the drum 10, this being accomplished by the fact that the 70 compartments 14 and 15 are shorter than the length of the drum 10.

A feed water supply pipe 20 communicates through the branches 21, 22 with the compartments 14 and 15, respectively. The feed water enters these compartments and passes down the central tubes of the rows 18 and 19 to the compartments 16 and 17, respectively, and from thence through the remainder of the 80 tubes of these rows into the main circulation of the boiler by way of the drum 10.

At the upper portion of each set of water tubes and on the sides away from the furnace chamber are superheater chambers which are designated generally as 23, 24. Each chamber is closed on its outer side and is open on the side adjacent the set of water tubes. In each chamber is a superheater which, in the form illustrated, is composed of headers 25, 26 of the usual type, the inlet headers 26 90 being connected through the pipes 27 with the saturated steam outlet 28. The superheater tubes, which are illustrated as of the U-shaped type, extend from the headers 25, 26 in the usual manner and lie crosswise of the sets of tubes 12', 13 in the chambers 95 23, 24.

In the form illustrated, the weight of the superheater tubes is carried on a support 29 100 extending upwardly from the lower drum

beneath the superheater headers. At the opposite end the U tubes may be supported by a rack 30 provided with a number of tongues each adapted to extend beneath a superheater tube, this rack being clamped to the rearmost 5 of the water tubes by any suitable device, such as clamps 31 and strap connections 32 connecting the upper end of the rack to the drum 10.

10 A baffle 33 extends from the lower water drum upwardly along the set of water tubes and, in the form shown, behind the second row of such tubes from the furnace chamber. The tops of the baffle 33 are removed from the upper drum 10 a sufficient distance to permit the gases from the furnace chamber to flow up along the baffle 33 and then enter among the water tubes at substantially right-angles thereto. At the upper ends of the baffle 15 33 are provided cross baffles 34 which extend substantially across the set of water tubes and therefore to the open side of the superheater chamber. At the lower end of each superheater chamber is 20 preferably provided a second cross baffle 35 which is short enough to permit the gases to pass between its lower end and the baffle 33. The parts are also proportioned so that the gases may pass between the baffle 35 and 25 the corresponding lower water drum.

30 Outside of the superheater chamber and the portions of the water tubes below such chambers, extend side walls 36, 37 which are removed from the superheater chamber and the tubes a sufficient distance to provide a gas 35 passage upwardly to the usual gas outlet. The walls 36 and 37 may be insulated in the usual manner to prevent the passage of heat.

35 The furnace gases rise along the baffles 33 and then divide with a portion passing into each of the sets of water tubes 12' and 13, in each of which the gases first pass across the water tubes at their upper ends and then flow over the superheater tubes in a generally 40 downward direction into the second pass between the baffles 34, 35 and from thence again across the tubes into the gas passage adjacent the side walls 36, 37 to the gas outlet.

45 It will be seen that, by providing the baffle 34, as shown, the gases are forced to flow entirely over the superheater tubes after the gases have passed across the upper part of the water tubes, and that the circulation to and from the water tubes and around the 50 superheater tubes is positive and definite, so that the operating conditions will not fluctuate unduly under different conditions of service. By interposing the superheater with its chamber between the water tubes and the gas 55 outlet, a minimum amount of heat that might be absorbed in generating the superheated steam is permitted to escape into the fire room through the side walls, as the spent gases 60 serve to assist in insulating the boiler and 65 superheater against such a loss. The sides

are in reality jacketed with the spent gases, which serve more effectively to prevent such a radiation loss than the non-conductive covering and casing ordinarily employed.

70 If desired, the baffle 35 may be omitted, and it will also be understood that the baffle 33 may be placed either entirely in front of the set of water tubes or behind as many as is found desirable. While it is desirable, for well known reasons, to provide a boiler with 75 a double set of water tubes as illustrated, it will be understood that certain parts of my invention may be applied to a boiler having one lower water drum only and one set of tubes. A double boiler of the type illustrated 80 is desirable, however, because by providing a set of water tubes and a superheater on either side of the furnace chamber, a minimum amount of heat is permitted to escape into the boiler room. Suitable dust doors 85 and dust blowers may be provided in the several passes, as shown, to free the tubes from dust.

90 The upper and lower water compartments are provided with the arrangement of the water tubes connecting these compartments, hereinbefore described, in order to purify the feed water as much as possible before the feed water enters the general circulation of the boiler. It is well known that water con- 95

taining certain impurities in particular will have such impurities precipitated by heating the water to a relatively high temperature. Such precipitation in itself, however, is of no advantage unless the precipitates have an 100 opportunity to settle down and thus become separated from the water. The best results will be obtained by first heating the feed water as rapidly as possible in its journey from the feed water inlet into the general water 105 circulation, so as to cause it to reach a temperature sufficiently high to cause precipitation at the beginning of this journey, and then allowing the water to travel over a relatively long path arranged so that the precipitates may separate out, and in which the 110 temperature of the water is being gradually raised but so as not to boil, and thus agitate the water until the precipitates have had an opportunity to settle out. The arrangement 115 of the water tubes connecting the compartments is particularly adapted to accomplish these ends. As the feed water passes from an upper compartment, as 15, it crosses the first pass, at which time the gases are still 120 very hot, since they have been cooled only by crossing the upper part of the water tubes once. In crossing this first pass, therefore, the relatively cold feed water is raised very 125 quickly to a temperature sufficiently high to cause precipitation. In the next portion of its journey downward, this water passes across the second pass in which the gases are considerably cooler than in the first pass by reason of their previous passage over the 130

superheater tubes. In the passage of this water across the third pass, it is contacted with the relatively cool gases which are passing to the gas outlet. In the lower water compartment, the water turns and flows substantially horizontally, and from thence upward through the remaining tubes of the rows 18 and 19. In these rows, the temperature of the water is gradually raised by reason of its passage across progressively hotter gas passages. It will be noted, therefore, that the feed water is first heated to a high temperature and that, in its continued travel downward and thence upward, additional heat is supplied in such a way that the temperature of the water is raised relatively slowly, and that, by reason of the direction of flow of the water, and particularly its spreading out in the lower compartment, the precipitates have full opportunity to settle out without being disturbed by the ebullition of boiling water.

For some purposes, some of the same results might be obtained by having the upper compartment connect with a lower compartment by a row of tubes extending entirely across the boiler, as the row 19, with the lower compartment connecting with the drum 10 through the entire row 18 of the tubes. Such an arrangement, however, would permit at least some of the water flowing downward through the tubes 19 to return immediately through the tubes 18 without remaining for any time in the compartment 16 or 17, and thus not be subjected to the settling action which results when the water necessarily travels horizontally in that chamber as it does with the arrangements which are illustrated.

Blow-off cocks are provided both for the lower water compartments and the lower water drums, such blow-off cocks being particularly desirable on the lower water compartments in order to remove the precipitates which may be thrown down and carried into those compartments from the feed water.

While, preferably, the upper and lower water compartments are formed directly in the upper and lower water drums, respectively, it will be understood that such compartments may be formed independently of these drums.

It will also be understood that any suitable type of superheater, other than the U-shaped one illustrated, may be used.

What is claimed is:

1. A steam boiler comprising an upper and a lower drum and a set of tubes connecting the drums and arranged in rows across the boiler, a furnace chamber adjacent the set of tubes, baffles arranged to cause the furnace gases to enter among the tubes at their upper ends and pass entirely across said upper ends and thence back and forth across the tubes in a generally downward direction, an upper

water compartment, a feed water supply connected thereto, and a lower water compartment, some of the rearmost tubes of the set connecting the upper and lower compartments and others of the rearmost tubes connecting the lower compartment with the upper drum.

2. A steam boiler comprising an upper and a lower drum and a set of tubes connecting the drums and arranged in rows across the boiler, a furnace chamber adjacent the set of tubes, baffles arranged to cause the furnace gases to enter among the tubes at their upper ends and pass entirely across said upper ends and thence back and forth across the tubes in a generally downward direction, an upper water compartment, a feed water supply connected thereto, and a lower water compartment, the tubes of one of the rear rows of the set being divided into three groups crosswise of the boiler, with the tubes of the central group connecting the upper and the lower compartments and the two end groups connecting the lower compartment and the upper drum.
